DESIGN FOR A CLEANER HEAD FOR DETERGING APPARATUS

Francis U. von Schrader, Racine, Wis.

Application August 16, 1937, Serial No. 71,125

Term of patent 14 years

To all whom it may concern:

Be it known that I, Francis U. von Schrader, a citizen of the United States, residing in Racine, in the county of Racine and State of Wisconsin, have invented a new, original, and ornamental Design for a Cleaner Head for Deterging Apparatus, of which the following is a specification, reference being had to the accompanying drawing, forming part thereof.

In the drawing:

I claim:

The ornamental design for a cleaner head for deterging apparatus, as shown.

FRANCIS U. VON SCHRADER.
